SCREW-THREADED PIVOTED CLOSURE

Marion P. Wall, Lookout Mountain, Tenn., assignor to Combustion Engineering Company, Inc., New York, N. Y., a corporation of Delaware

Application November 8, 1946. Serial No. 708,607

13 Claims. (Cl. 220—30.5)

1

This invention relates to closures for access openings and the like in vessels subjected to internal pressures (either high or low) of which drums or bottles used for dry ice liquefiers constitute an illustrative example.

Closures for dry ice liquefiers are located at one end of a relatively long cylindrical drum or bottle and must be easily and quickly opened and closed. The pressures within such a liquefier vary from atmospheric upon being filled with dry ice, to about 1400 p. s. i. after being closed when the dry ice becomes fluid. The closure includes a head capable of resisting the maximum pressure within the bottle, a gasket for effectively sealing the space between the head and bottle, and means associated with the head and gasket for transferring the pressure on the inside of the head through the gasket to the walls of the bottle.

For quick opening and closing, the entire closure should be capable of being removed as a unit while being supported from the bottle. The head, gasket and means for transferring the pressure on the head to the bottle should, when being opened, preferably remain in the relative positions they occupy when they are in closed position and should be protected from injury while opening and when in open position.

It is an object of this invention to provide such an improved closure for the above and other pressure vessels.

Other objects and advantages will become apparent as the description hereof proceeds.

An illustrative form of the invention is shown by the accompanying drawings wherein:

Figure 1 is a view in front elevation of my improved closure applied to an access hole in a high pressure vessel;

Figure 2 is a plan view of the new closure in closed position showing a portion thereof in section as taken along line 2—2 of Figure 1; and

Figure 3 is a plan view of the closure in open position showing a portion thereof in section as taken along line 3—3 of Figure 1.

Referring first to Figure 2, the access opening to be closed is shown as being formed in a high-pressure drum or bottle having a cylindrical side wall 10 and an end portion 11 which defines the opening. That drum end 11 is provided with an inwardly projecting upset portion 12 which has upon its inner surface threads 13 extending inwardly from the drum's end face, a cylindrical surface 14 extending inwardly from those threads towards the drum's opposite end (not shown) and of smaller diameter than threads 13, and a

2

constricting shoulder 15 at the base of surface 14 having the still smaller internal diameter indicated.

Referring next to Figures 1-2-3, the closure of my invention is there shown as being applied to this opening in drum end 11. This closure comprises a head 16 (see Figures 2 and 3), an annular ring 17 for retaining the head, a gasket 18 interposed between the head and ring, and an external ring-like door member or cap 19. This closure cap or door member 19 is hinged to drum head 11 by means of spaced lugs 20 on the cap, associated spaced lugs 21 on the drum, and a hinge bolt 22 extending through holes within lugs 15 in the usual manner.

The closure head 16 has a thickness sufficient to withstand the maximum pressure within the drum 10. This head 16 is provided with a flange portion 23 adjacent its inner or leading face 24, the outer circumferential face 25 of which flange portion is slightly conically contracting toward the inner face 24 and fits closely within the cylindrical surface 14 of the drum end 11. The head's opposite or trailing portion is encircled by the represented circumferential recess which extends from flange 23 to the outer or trailing face 26 of the head. When in the position shown in Figure 2 the head 16 rests against shoulder 15 of the drum end 11 which stops its further movement into the drum. Fastened centrally to the outer or trailing face 26 of the head is a stud bolt 27 which extends axially outward therefrom, as shown in Figure 3, for a purpose later to be explained.

The closure's ring 17 is provided on its outer circumferential surface with threads 28 which engage the threads 13 provided on the inner portion 12 of the drum end 11. The inner or leading face 29 of ring 17 has an outer diameter that permits it to enter the drum head with a close fit and the ring 17 has a radial thickness adjacent said face substantially equal to the radial depth of the gasket 18 in head 16. The outer or trailing face of this ring 17 is provided beyond the ends of the threads 28 with a circumferential face 30 which extends beyond the end of the drum end 11 and into the door-member cap 19 as shown in Figure 2.

As shown in Figure 3, the outer or trailing end 50 of closure ring 17 has welded thereon a conically-formed plate 31 having a central hole 32 through which the stud bolt 27 from head 16 projects. By means of nuts 33 and washer 34 the plate 31, ring 17 and head 16 are at all times maintained 55 in such spaced relation as to retain the gasket 18

and a gasket ring 35 between the ring 17 and the head flange 23. Fastened to plate 31 and spaced therefrom by legs 36, is a hand bar 37 by which the annular ring 17 may be rotated and screwed either out of or into the drum end 11. This bar and its supporting legs 36 extend in the manner shown through closure cap 19's central opening 39.

The inner circumferential face of this closure cap or ring-like door member 19 is further provided with threads 38 which are identical (of the same diameter and size) with the threads 13 in the drum end 11 and which mesh with the threads 28 on the ring 17. At circumferentially spaced points around door member cap 19 are extension portions 40a through which adjusting screws 41 project to abut the end face of drum head 11 as shown in Figure 2. These screws 41 are set to maintain the inner face of the cap in such spaced relation with the outer face of the drum end 11 that the threads 13 of drum end 11 are continuous with the threads 38 in the door member cap 19 when the cap is in the closed, aligned position of Figure 2. Once set in proper position each screw 41 may be locked against turning by a jamb nut (not shown) or other well known means.

By so spacing the drum end and door member closure cap, the closure ring 17 may be withdrawn from the drum end into the cap by screwing it outwardly by means of the hand bar 37. A lug 42 which is welded to the drum end 11 cooperates with a lug 43 on the ring-like cap 19 to guide that door-member cap into alignment with the drum end when the cap is closed.

After the closure ring 17 has been withdrawn from the drum end 11 and screwed back into the door-member cap 19 it will occupy a position as shown in Figure 3. Since stud bolt 27 holds the ring 17 and head 16 together the entire assembled head 16, ring 17 and gasket 18 are drawn into the ring-like cap 19 in the same relative positions (of Figure 2) that they occupied in the drum end. As the door-member cap is swung open about hinge bolt 22, as shown in Figure 3, the threads and gasket thus are protected from injury by the cap and are retained in position to be screwed back into the drum end when the ring-like cap is again closed against the drum end.

For holding the external closure cap 19 in properly aligned closed position while the closure ring 17 is being screwed from the cap into the drum end 11, a spring loaded latch 44 is provided on the drum end to engage the flange 40 of door-member cap 19 when the latch has the position of Figures 1-2. Latch rotation through 90 deg. releases this engagement and frees cap 19 for withdrawal.

In order to replace the gasket 18 in the closure assemblage, the nuts 33 of stud bolt 27 may be removed and closure ring 17 together with closure plate 31 then withdrawn over the stud and from the closure head 16. The gasket ring 35 and gasket 18 may now be removed and replaced.

It will be evident from the foregoing that gasket 18 is radially expandable into sealing contact with the opening's side wall when axially compressed between closure head 16 and ring 17, as in the position of Figure 2; that as the ring is screwed by bar 37 into the opening wall threads, the leading end 24 of head 16 abuts vessel 10's constricting shoulder 15 so that further advancement of ring 17 builds up the named axial

compression on and radial expansion of gasket 18 to establish the closure seal; and that high pressure subsequently generated within vessel 10 urges closure head 16 more strongly against gasket 18 (backed by closure ring 17 therebehind), thereby intensifying the seal in desired manner.

It will be further evident that a withdrawal of closure ring 17 by reverse rotation in the opening side wall threads releases the gasket compression and breaks the closure seal; that continuing withdrawing rotation of the ring transfers the ring-head-gasket assemblage into the threaded closure cap 19 aligned with the vessel opening as in Figures 1-2; and that outward swinging of that door-member cap about hinge bolt 22 bodily transfers the named closure parts to the position of Figure 3 where those parts are effectively protected by the ring-like cap against mechanical injury and held in immediate readiness for reinsertion into the vessel opening.

What I claim is:

1. In a closure device for a pressure-vessel opening that comprises a closure head enterable into the opening, a gasket carried by the head, a closure ring trailing the gasket and removably secured to the head, mating threads on the closure ring's periphery and on the vessel opening's interior surface, an element fastened to and trailing the closure ring for imparting thereto rotation which screws the ring into and out of the vessel opening, and means in said opening to limit entering advancement of the closure head so that inward screwing of the closure ring will compress the gasket, the combination of an external ring-like door member movably supported by the pressure vessel for placement into or out of alignment with said opening and being formed to permit outward projection of said closure-rotating element therethrough, and threads on the inside of said ring-like door member for engaging the threads on said closure ring whereby that closure ring, head and gasket may as an assemblage be screwed out of the opening into the door member for movement away from the opening therewith and out of the door member back into the opening when it is desired to reclose and seal the pressure vessel.

2. In a closure device for a pressure-vessel opening that comprises a closure head enterable into the opening, a gasket surrounding said head behind a leading flange thereon, a closure ring surrounding the trailing head portion behind said gasket, tie means retaining said head and ring together with the gasket therebetween, mating threads on the closure ring's periphery and on the vessel opening's interior surface for enabling the ring to be screwed into and out of the opening by advancing and withdrawing rotation thereof, and means in the vessel opening to limit entering advancement of the closure head so that inward screwing of the closure ring will compress the gasket, the combination of an external ring-like door member hinged to the pressure vessel adjacent said opening so as to axially align therewith when closed thereagainst and at other times to be swingable outwardly completely away from the opening, and threads on the inside of said ring-like door member for engaging the threads on said closure ring whereby that closure ring, head and gasket may as an assemblage be screwed out of said opening into the door member for swinging away from the opening therewith and out of the door member back into the opening when it is desired to reclose and seal the pressure vessel.

3. In a closure device for a pressure-vessel opening that comprises a closure head enterable into the opening, a gasket surrounding said head behind a leading flange thereon, a closure ring surrounding the trailing head portion behind said gasket, tie means retaining said head and ring together with the gasket therebetween, mating threads on said closure ring's periphery and on the vessel opening's interior surface for enabling the ring to be screwed into and out of the opening by advancing and withdrawing rotation thereof, and means in the vessel opening to limit entering advancement of said head so that inward screwing of the closure ring will compress the gasket, the combination of an external door member having a circular rim and being hinged to the pressure vessel adjacent said opening so as to axially align therewith when closed thereagainst and at other times to be swingable outwardly completely away from the opening, and threads on the inside of said door member rim for engaging the threads on said closure ring whereby that closure ring, head and gasket may as an assemblage be screwed out of said opening into the door member for swinging away from the opening therewith and out of the door member back into the opening when it is desired to reclose and seal the pressure vessel.

4. In a closure for an opening in a pressure vessel, the combination of a closure head enterable into said opening, a gasket carried by said head, a ring trailing said gasket and tie to said head, mating threads on said ring's periphery and on said opening's interior surface, a member fastened to and trailing said ring for imparting thereto rotation which screws the ring into and out of said opening, means in said opening to limit entering advancement of said head so that inward screwing of the ring will compress said gasket and seal the opening, an external closure cap movably supported by said vessel for placement into or out of alignment with said opening and being formed to permit outward projection therethrough of said ring rotating member, and threads in said cap for engaging the threads on said closure ring whereby that ring, head and gasket may as an assemblage be screwed out of said opening into said cap and out of said cap into said opening.

5. In a closure for an opening in a pressure vessel, the combination of a closure head enterable into said opening, a gasket surrounding said head behind a leading flange thereon, a closure ring surrounding the trailing head portion behind said gasket, tie means retaining said head and ring together with the gasket therebetween, mating threads on said ring's periphery and on said opening's interior surface for enabling said ring to be screwed into and out of said opening by advancing and withdrawing rotation thereof, means in said opening to limit entering advancement of said head so that inward screwing of the ring will compress said gasket and seal the opening, an external closure cap hinged to said vessel adjacent the opening so as to axially align therewith when closed thereagainst and to be swingable outwardly completely away from the opening, and threads in said cap for engaging the threads on said closure ring whereby that ring, head and gasket may as an assemblage be screwed out of said opening into said cap and out of said cap into said opening.

6. In a closure for an access opening in a pressure vessel, the combination of a closure head enterable into said opening and having in its

leading portion a circumferential flange axially adjoined on the head's trailing portion by a circumferential recess for the reception of a gasket; an annular gasket in said recess encircling said head and radially expandable into sealing contact with the inner surface of said opening when axially compressed against said flange; a closure ring axially fittable over the recessed portion of said head against said gasket to effect said compression and being enterable into said opening with said head in trailing relation thereto; a plate fastened to the trailing end of said ring and a hand bar fastened to the outer side of said plate; central tie means between said head with said ring plate for retaining said head and ring together with the gasket therebetween; mating threads on said ring's periphery and on said opening's interior surface for enabling said ring to be screwed into and out of said opening by advancing and withdrawing rotations imparted thereto through said bar; a constriction positioned in said opening to limit entering advancement of said head so that inward screwing of said ring will compress said gasket and seal the opening as aforesaid; an external closure cap movably supported by said vessel for placement into or out of alignment with said opening and being formed to permit outward projection therethrough of said ring-rotating hand bar; and threads in said cap for engaging the threads on said closure ring whereby that ring, head and gasket may as an assemblage be screwed out of said opening into said cap and out of said cap into said opening.

7. In a closure for an access opening in a pressure vessel, the combination of a closure head enterable into said opening and having on its leading portion a circumferential flange axially adjoined on the head's trailing portion by a circumferential recess for the reception of a gasket; an annular gasket in said recess encircling said head and radially expandable into sealing contact with the opening's side wall and the head when axially compressed against said flange; a closure ring axially fittable over said recessed head body against said gasket to effect said compression and enterable into said opening with said head in trailing relation thereto; mating threads on said ring's periphery and on said opening's side wall for enabling said ring to be screwed into and out of said opening by appropriate rotation of the ring; a constricting shoulder positioned in said opening to limit entering advancement of said head so that inward screwing of the ring will compress said gasket and seal the opening as aforesaid while outward screwing of the ring will release and break the seal; means for retaining said head and ring together with the gasket therebetween even after these closure parts are withdrawn from said opening; an external closure cap movably supported by the vessel for placement into or out of alignment with said opening; and threads in said cap for engaging the threads on said ring whereby the ring, head and gasket may be withdrawn from said opening into said cap and removed therewith from said opening.

8. In a closure for an access opening in a pressure vessel, the combination of a closure head enterable into said opening and provided with a leading circumferential flange and a trailing circumferential recess; an annular gasket in said recess in abutment with said flange; a closure ring axially fittable over the recessed head portion against said gasket and enterable into said open-

ing with said head in trailing relation thereto; mating threads on said ring's periphery and on said opening side wall for enabling said ring to be screwed into and out of said opening; means protruding from the trailing portion of said ring for imparting rotation thereto; a constricting shoulder positioned in said opening to limit entering advancement of said head so that inward screwing of said ring will compress said gasket and seal said opening; means for retaining said head and ring together with the gasket therebetween even after these closure parts are withdrawn from said opening; an external cap having an open top through which said ring-rotating means extends and being movably supported by the vessel for placement into or out of alignment with said opening; and thread in said cap for engaging the threads on said ring whereby the ring, head and gasket may be withdrawn from said opening into said cap and removed therefrom with said opening.

9. In a closure for an access opening in a high pressure vessel, the combination of threads on said opening's interior extending from the outside axially thereinto; a cylindrical interior surface axially beyond said threads within said opening and being of a diameter no greater than that which the thread tops define; a constricting shoulder at the inner end of said cylindrical surface defining a still smaller diameter; a cylindrical head removably enterable into said opening to close same having an inner flange portion fitting into said surface and engaging said constricting shoulder when in closed position and also having an outer smaller portion forming a circumferential gasket recess adjacent said cylindrical surface; a removable closure ring having an inner portion formed to fit axially over said head's smaller portion into said gasket recess and having an outer portion provided with threads engageable with said threads on said opening's interior; a gasket in said recess compressible between said ring and said head's inner shoulder portion for sealing contact with the opening's cylindrical surface; means fastened to said ring for imparting thereto rotation which screws the ring into and out of said opening; means fastened to said head and to said ring to maintain said head and said ring in axially spaced relation with said gasket therebetween as aforesaid; and a cap having a wall hinged to the vessel adjacent the access opening so as to swing the cap into axial alignment therewith when in closed position, the inside of said wall having threads of the same diameter and size as the threads on said vessel whereby the ring, head and gasket may be withdrawn from said opening into said cap and then swung away from said opening with the cap.

10. In a closure for an access opening in a high pressure vessel, the combination of helical threads on the opening interior extending axially into the opening; a cylindrical surface on said interior axially beyond the inner ends of said threads and having a diameter no greater than that which the thread tops define; a constricting shoulder at the inner end of said surface defining a still smaller diameter; a removable cylindrical head to close said opening having an inner flange portion fitting into said surface and engaging said constricting shoulder when in closed position and also having an outer smaller portion forming a circumferential gasket recess adjacent said cylindrical surface; a removable closure ring hav-

ing an inner portion formed axially over said head's smaller portion into said gasket recess and having an outer portion provided with helical threads engageable with said threads on said opening's interior; a gasket in said recess compressible between said ring and said head's inner flange portion for sealing contact with the opening's cylindrical surface; means fastened to said ring for imparting thereto rotation which screws the ring into and out of said opening; means fastened to said head and to said last means to maintain said head and said ring in axially spaced relation with said gasket therebetween as aforesaid; and a cap having an open top through which said ring rotating means extends and a wall hinged to the vessel adjacent the access opening so as to swing the cap into axial alignment therewith when in closed position, the outside of said wall having helical threads of the same diameter and size as the threads on said vessel whereby the ring, head and gasket may by rotation of the threaded ring be withdrawn from said opening into said cap and then swung away from said opening with the cap.

11. In a closure for an access opening in a pressure vessel, the combination of a closure head enterable into said opening and having on its leading portion a circumferential flange axially adjoined on the head's trailing portion by a circumferential recess for the reception of a gasket; an annular gasket in said recess encircling said head and radially expandable into sealing contact with the inner surface of said opening when axially compressed against said flange; a closure ring axially fittable over said recessed head portion against said gasket to effect said compression and enterable into said opening with said head in trailing relation thereto; mating threads on said ring's periphery and on said opening's inner surface for enabling said ring to be screwed into and out of said opening by advancing and withdrawing rotation of the ring; a constriction positioned in said opening to limit entering advancement of said head so that inward screwing of said ring will compress said gasket and seal the opening as aforesaid while withdrawing rotation of the ring will release and break the seal; means for retaining said head and ring together with the gasket therebetween even after these closure parts are withdrawn from said opening; and a cap with a cylindrical wall having an axial depth equal at least the sum of the axial depths of said ring and gasket, the cap being hinged to said vessel adjacent said access opening so as to swing into axial alignment therewith when in closed position, the inside of said wall having threads mating those on said opening interior whereby the closure ring, head and gasket may as an assemblage be screwed out of said opening into said cap and then swung away from the opening with the cap.

12. In a closure for an access opening in a pressure vessel, the combination of a closure head enterable into said opening and having on its leading portion a circumferential flange axially adjoined on the head's trailing portion by a circumferential recess for the reception of a gasket; an annular gasket in said recess encircling said head and radially expandable into sealing contact with the inner surface of said opening when axially compressed against said flange; a closure ring axially fittable over said recessed head portion against said gasket to effect said compression and enterable into said opening with said

75

head in trailing relation thereto; mating threads on said ring's periphery and on said opening's inner surface for enabling said ring to be screwed into and out of said opening by advancing and withdrawing rotation of the ring; a constriction positioned in said opening to limit entering advancement of said head so that inward screwing of said ring will compress said gasket and seal the opening as aforesaid while withdrawing rotation of the ring will release and break the seal; means for retaining said head and ring together with the gasket therebetween even after these closure parts are withdrawn from said opening; a cap with a cylindrical wall having a depth equal at least the sum of the axial depths of said ring and gasket, the cap being hinged to said vessel adjacent said access opening so as to swing into axial alignment therewith when in closed position, the inside of said wall having threads mating those on said opening interior; and set screws carried by said cap engaging said vessel around the opening to space the cap with respect thereto so as to cause the mating threads in said cap and on said opening interior to be continuous whereby the threaded ring, head and gasket may as an assemblage be screwed out of said opening into said cap and then swung away from the opening with the cap.

13. In a closure for an access opening in a pressure vessel, the combination of a closure head enterable into said opening and having on its leading portion a circumferential flange axially adjoined on the head's trailing portion by a circumferential recess for the reception of a gasket; an annular gasket in said recess encircling said head and radially expandable into sealing contact with the inner surface of said opening when

axially compressed against said flange; a closure ring axially fittable over said recessed head portion against said gasket to effect said compression and enterable into said opening with said head in trailing relation thereto; mating threads on said ring's periphery and on said opening's inner surface for enabling said ring to be screwed into and out of said opening by advancing and withdrawing rotation of the ring; a constriction positioned in said opening to limit entering advancement of said head so that inward screwing of said ring will compress said gasket and seal the opening as aforesaid while withdrawing rotation of the ring will release and break the seal; means for retaining said head and ring together with the gasket therebetween even after these closure parts are withdrawn from said opening; a cap with a cylindrical wall hinged to the vessel adjacent said access opening so as to axially align therewith when in closed position, the inside of said wall having threads mating those on side opening interior; set screws carried by said cap engaging said vessel around the opening to space the cap with respect thereto so as to cause the mating threads in said cap and on said opening interior to be continuous; a lug fastened to said vessel adjacent the opening and supporting the cap when closed for aligning the axis of the cap with that of the access opening; and a spring loaded latch fastened to the vessel also adjacent said opening to engage the cap and hold said set screws against said vessel whereby the threaded ring, head and gasket may as an assemblage be screwed out of said opening into said cap and out of said cap into said opening.

MARION P. WALL.
